UNITED STATES PATENT OFFICE.

ELLERY L. EASTLING, OF PLAINFIELD, WISCONSIN, ASSIGNOR OF ONE-HALF TO LEON W. EASTLING, OF PLAINFIELD, WISCONSIN.

RAILROAD-SPIKE.

No. 910,364.

Specification of Letters Patent.

Patented Jan. 19, 1909.

Application filed May 4, 1908. Serial No. 430,749.

To all whom it may concern:

Be it known that I, ELLERY L. EASTLING, a citizen of the United States, residing at Plainfield, in the county of Waushara and State of Wisconsin, have invented certain new and useful Improvements in Railroad-Spikes, of which the following is a specification, reference being had to the accompanying drawings.

10 My invention relates to improvements in spikes and securing or locking means therefor.

The object of the invention is to provide a spike which will effectively fasten a track rail to a wooden cross tie and which will be securely locked by a key wedge of peculiar construction.

With the above and other objects in view, the invention consists of the novel features of 20 construction and the combination and arrangement of parts hereinafter fully described and claimed, and illustrated in the accompanying drawings, in which—

Figure 1 is a vertical section through a 25 track rail, a portion of a wooden cross tie and my improved spike; Figs. 2 and 3 are side and edge views of the spike with the key wedge therein; and Figs. 4 and 5 are detail views of the key wedge.

30 In the drawings 1 denotes a track rail, 2 a wooden cross tie; 3 my improved fastening spike and 4 its locking key or wedge. The spike 3 has a body or shank of rectangular shape in cross section, the lower end of which 35 has its sides beveled in opposite directions to form a point 5 so that the spike may be readily driven into the tie. The upper end of the body of the spike is formed with a head 6, a portion of which is disposed over said end of 40 the body and a portion of which projects laterally from the inner side of said body to provide a lip or projection 7 to engage the base flange of the rail. The head 6 is of greater width than the width of the body of the spike 45 so that at opposite sides of the head are formed projecting shoulders 8 which may be readily engaged by a spike extractor when it is desired to remove the spike. The under portion of the projection or lip 7 is curved or 50 rounded, as at 9, to fit the edge of the base flange of the rail and said portion of the head is thickened, as illustrated, to strengthen it. The outer face of the body 3 is flat from its 55 tapered lower end or point to its top or head 6 and formed in the upper portion of the

body and extending angularly or diagonally through it from its outer to its inner face is a slot or opening 10 to receive the key wedge 4. Said slot 10 extends downwardly and inwardly from the outer to the inner face of the spike and the bottom wall 11 of said slot is inclined downwardly to a greater extent than the upper wall 12 of the same so that said slot is flared or larger upon the inner side of the body 3 than upon the outer side of the 65 same. The key wedge 4 has a flat body of rectangular shape in cross section which tapers from its upper to its lower end, which latter terminates in a point 13. In the opposite side faces of the body of the key wedge 70 are formed transverse grooves which provide transverse retaining teeth 13^a. At the upper end of the body of the key wedge is an enlarged flat and substantially triangular shaped head 14, the chief function of which 75 is to brace the upper portion and head of the spike. This head or enlarged portion 14 of the key wedge has one of its edges straight and forming a continuation of one edge of the flat body of the key wedge and another 80 edge 15 of said head or enlargement 14 is disposed at an angle to the opposite edge of the body and is adapted to bear against the flat outer face of the spike and to project slightly above the head of the latter. The third edge 85 16 of the triangular shaped head or enlargement of the key wedge, which edge forms the extreme upper end of the latter, has its inner portion enlarged or formed with laterally projecting ribs 17 which form shoulders for 90 the engagement of a spike extractor or similar tool. By constructing the head of the key wedge in this manner it will be seen that the latter may be removed by the ordinary extracting tool or device used for extracting 95 the spike.

By making the slot 10 flaring or of greater width upon the inner face of the spike than upon its outer face and by making the head 14 of the key wedge of triangular shape so 100 that one of its edges 15 bears against the body of the spike adjacent its head, it will be seen that when the track rail tends to move outwardly and to shift the spike, said head 14 of the key wedge will effectively brace the spike and the back of its head, thereby causing it to more effectively hold the rail and prevent the latter from spreading. The peculiar construction of the key wedge also prevents the spike from turning and prevents 110

it from pulling out and loosening even when portions of the tie have decayed.

The key wedge may be applied to any spike that is slotted to receive it and it will 5 not only retain the spike in the tie but also effectively brace it, as above noted. The peculiar shape of the head of the key wedge permits it to be readily extracted and also prevents rain water from working down into 10 the tie and rotting it.

Having thus described my invention what I claim is:

1. The combination with a spike having a slot extending through it in a downward and 15 inward direction from its outer to its inner face, of a key wedge passed through said slot and having one end tapered and its other end formed with an enlargement or head having an upstanding portion to bear against the 20 outer side face of the body and head of the spike, substantially as and for the purpose set forth.

2. The combination with a spike having a body formed at one end with a point, at its

other end with a laterally projecting head 25 disposed upon its inner side, and in its intermediate portion adjacent to said head with a slot inclined downwardly and inwardly from its outer to its inner face, of a key wedge inserted in said slot and having one end 30 tapered to a point and its other end formed with a substantially triangular shaped enlargement or head, one edge of the latter being straight and forming a continuation of one end edge of the body of the key wedge, 35 another edge of said head of the key wedge being disposed at an angle to the opposite edge of its body and being adapted to bear against and brace the outer or back portion of the head of the spike, substantially as and 40 for the purpose set forth.

In testimony whereof I hereunto affix my signature in the presence of two witnesses.

ELLERY L. EASTLING.
